UNITED STATES PATENT OFFICE

127,984

DESIGN FOR A THERMOMETER

Daniel D. Whyte, Brooklyn, N. Y., and William Anton Lang, Springfield, Mass.; said Lang as signor to said Whyte

Application April 25, 1941, Serial No. 100,614

Term of patent 7 years

To all whom it may concern:

Be it known that we, Daniel D. Whyte, and William Anton Lang, citizens of the United States and residents, respectively, of the Borough of Brooklyn, county of Kings, State of New York, and Springfield Massachusetts, with post office addresses, respectively, at 113 Fourth Avenue, in the city, county, and State of New York, and 99 School Street, Springfield, Massachusetts, have invented a new, original, and ornamental Design for Thermometers, of which the following is a specification, reference being had to the accom-

panying drawing, forming part thereof, in which Figure 1 is a front elevation of a thermometer showing our new design.

Figure 2 is a side elevation of the same.

Figure 3 is a fragmentary sectional view taken along lines 3—3 of Figure 1.

We claim:

The ornamental design for a thermometer, as shown.

DANIEL D. WHYTE.

WILLIAM ANTON LANG.
